ABSTRACT

The load limiting apparatus of a tower crane, which inactivates the load lifting winch when a predetermined load is exceeded, is controlled in such a manner that the maximum permissible load L_{max} varies with the angle α between the boom and the horizontal, and the corresponding horizontal spacing a between the projections of the boom pivot and of the depending load carrying cable in a manner to satisfy the equation $L_{max} = L_{0max} - k_1 a$ wherein L_{0max} is the value of L_{max} when a is at a minimum, and k_1 is a proportionality factor and constant for all practical purposes. Under these conditions, the maximum tensile stress developed in the boom is constant, at least for an optimum boom length, while a varies between a_{min} and a_{max} , and the structural strength of the material can be fully utilized under all conditions.

TOWER CRANE WITH LOAD LIMITING APPARATUS

BACKGROUND OF THE INVENTION

This invention relates to tower cranes, and particularly to tower cranes equipped with an improved load limiting apparatus.

The stresses in the boom of a tower crane at a fixed load vary as the horizontal spacing between the tower and the load varies, that is, as the boom is raised and lowered. To avoid failure of the boom, known tower cranes are equipped with load limiting apparatus which inactivates the load lifting winch or winches when a load applied to a load lifting tension member, such as a cable, rope, or chain, exceeds a value L_{max} which varies with the horizontal spacing a of the load or of the depending part of the load lifting tension member from the tower, more specifically from the pivot of the boom, as determined by the equation

$$aL_{max} = \text{constant}$$

This equation has its root in the historical development of crane construction. The term aL_{max} was used in the early days of tower crane construction as a guide in the selection of a counterweight which was preferably made one-half aL_{max} for best stability of the crane.

With the increasing height of tower cranes, the load moment aL_{max} is no longer the primary factor determining the stability of the crane because it does not reflect the effects of wind pressure. Modern tower cranes are therefore equipped with central ballast sufficient to absorb the forces exerted by wind and by the load under all usual conditions, yet, the load limiting devices employed heretofore were still designed to make the permissible maximum load inversely proportional to the horizontal distance between the load and the crane tower.

It has now been found that the conventional load limiting devices do not permit loading of a tower crane to the full design capacity of its structure, and it is a primary object of this invention to permit larger loads to be safely lifted by tower cranes without increasing the weight and cost of its structure.

SUMMARY OF THE INVENTION

According to this invention, a tower crane may safely be loaded to a maximum load L_{max} determined by the equation

$$L_{max} = L_{0max} - k_1 a$$

wherein L_{0max} is the permissible maximum load when a is a_{min} , that is, the spacing between the load and the pivot of the boom, projected into a common horizontal plane, is at the smallest available value, and k_1 is proportionality factor which is practically constant. Within limits set by the deviation of k_1 from a perfectly constant value, the equation presented above is that of a straight line, whereas the equation $aL_{max} = \text{constant}$ is that of a curve.

The higher permissible load in a crane equipped with a load limiting device of the invention has been found not to affect the stability of a conventional tower crane with its central ballast.

It has furthermore been found that a load limiting device which inactivates the load lifting winch when L_{max} exceeds the value determined by the above equation causes the maximum stress in the crane boom to be

practically uniform for all values of a for at least one specific boom length readily ascertained by calculation, and that the stresses in the boom under the permissible maximum load are held near the design stress at all angles of inclination of the boom, thereby permitting the structural strength of the boom to be utilized to its fullest advantage. The boom employed is preferably loaded in compression only and free from bending stresses other than those caused by its own weight.

10 Other features and objects of the invention will presently become apparent.

BRIEF DESCRIPTION OF THE DRAWING

FIG. 1 shows a tower crane equipped with the load limiting device of the invention;

FIG. 2 shows a portion of the tower crane of FIG. 1 including the load limiting device of the invention.

FIG. 3 is a diagram illustrating the relationship of the maximum permissible load L_{max} and the horizontal spacing a of the load from the tower for booms of different length in a tower crane equipped with a conventional load limiting device;

FIG. 4 illustrates the relationship of permissible load L_{max} and the horizontal spacing of the load from the tower for a tower crane equipped with a protection device of the invention, but otherwise analogous to the crane referred to in FIG. 3;

FIG. 5 shows the improvement (%) of the load bearing capacity of the crane of the invention as compared to an otherwise analogous crane as a function of the angle of inclination of two booms of different length;

FIG. 6 illustrates the maximum tensile stresses in booms of different length in a crane equipped with the conventional load limiting device as a function of the inclination of the boom; and

FIG. 7 shows the corresponding maximum tensile stresses in a crane according to the invention.

DESCRIPTION OF THE PREFERRED EMBODIMENT

The tower crane of the invention illustrated in FIG. 1 has a base structure 10 including a vehicular lower part 12 whose center portion 14 provides a bearing for a turntable 16. The tower proper 18 of the crane is mounted on the turntable 16 and is a vertical column having an obliquely inclined head portion 20. The boom 22 of the crane is a compression member, not subjected to significant bending stresses, and one of its ends is secured to the upper end of the column 18 by a pivot 24.

The boom 22 is angularly adjusted on the pivot 24 by a cable or cable system 26 which is operated by a winch 28 on the turntable 16 and, passing over guide pulleys 30, 34 on a rearwardly extending jib 32 and on the head portion 20, it is attached to the boom 22 near its front or free end by a suitable fastener 36. One end of the jib 32 is suspended from the head portion 20 by a cable 33.

A load may be raised or lowered by a lifting cable 38 operated by a winch 40 on the turntable 16. The cable 38 is trained over guide pulleys 42, 44, 46 respectively mounted on the jib 32, the head portion 20, and the front end of the boom 22, and a reversing pulley on a hook 48 to be fastened to an attachment 50 on the boom 22 near the free end of the latter.

60 The tower column 18 has upright front and rear frames 52, 54 which are connected by oblique braces 53 and by horizontal struts 3 of which one, of U-shaped

cross section, is shown in FIG. 2. The end of the jib 32 remote from the cable 33 is fastened to the illustrated strut 3 by a pivot 4. The guide pulley 42 is mounted on a bracket 56 attached to the jib 32 by a pivot pin 58. A switch actuating abutment 60 is mounted on the bracket 56 adjacent a switch 62 arranged on a post 63 which is fixedly mounted on the jib 32.

The abutment 60 is normally held out of engagement with the switch 62, as shown in FIG. 2, by a helical compression spring 64 coiled about a pin 68. The two axial ends of the spring 64 respectively abut against a guide sleeve 66 pivotally mounted on the bracket 56 and slidably receiving the pin 68, and against a collar 70 on the pin 68. A rod 72 coaxially attached to the pin 68 is secured to the boom 22 by a pivot pin 74. The pivot pin which attaches the sleeve 66 to the bracket 56 may be shifted between several bearing openings in the bracket 56 for adapting the load limiting device to different boom lengths.

The tension in the load lifting cable 38 tends to pivot 20 the bracket 56 clockwise as viewed in FIG. 2. When the load is sufficient to overcome the restraint of the spring 64, the switch 62 operates a relay circuit in a control box 76 in a conventional manner and stops the winch 40. A load exceeding the maximum load determined by the limiting device thus cannot be lifted.

The operating characteristics of the load limiting device of this invention will be described hereinafter with reference to dimensions indicated in FIGS. 1 and 2, wherein h is the distance between the pivot axes of the pivot pins 24, 74 engaging the boom 22, and α is the angle of inclination of the elongated boom 22 relative to the horizontal.

FIG. 3 illustrates the relationship between the maximum permissible load L_{max} and the effective horizontal spacing a of the load from a crane tower equipped with conventional load limiting devices. The full length of the boom is assumed to be 45 meters, and separate curves are shown for operation at full boom length (100 percent) and with booms shortened in steps of one-eighth to 87.5 percent, 75 percent, and 62.5 percent respectively.

The abscissa indicates the distance a (see FIG. 1) between the pivot 24 and the load hook 48 projected into a horizontal plane, and it varies for a boom of a given length with the angle α of boom inclination. The ordinate is calibrated in metric tons. The curves representing the relationship between maximal permissible load and horizontal spacing of the load from the pivot 24 of the boom 22 on the tower 18 are curves whose concave faces are directed toward higher loads. They are characteristic of tower cranes equipped with conventional load limiting devices.

When the same tower crane was equipped with the load limiting device of the invention described with reference to FIG. 2, and the relationship of maximum permissible load and effective horizontal spacing of load and tower was again determined and charted in the manner of FIG. 3, the graph of FIG. 4 was obtained in which the relationship between maximum load and effective horizontal load spacing is practically linear for booms of all tested lengths.

The lines shown in FIG. 4 satisfy the equation

$$L_{max} = L_{0max} - k_1 a \quad (I)$$

wherein L_{max} is the maximum load capacity to be determined, and L_{0max} is the maximum load permissible for minimum effective horizontal spacing a . In the crane chosen as an example, the smallest available, horizontal spacing a of the hook 48 and the pivot 24 is 12.9 meters; k_1 is a constant proportionality factor.

Because of the relationship of the load spacing, the angle α of boom inclination, and the effective length l of the boom, equation (I) may be rewritten as

$$L_{max} = L_{0max} - k_1 l \cos \alpha \quad (II)$$

The force exerted on the guide pulley 42 by the load lifting cable 38 is directly proportional to the load supported by the cable. At maximum permissible load L_{max} , the corresponding effective force R_s exerted by the cable on the pulley reaches the value

$$R_{Smax} = k_2 L_{max} \quad (III)$$

and

$$= k_2 L_{0max} - k_2 k_1 l \cos \alpha \quad (IV)$$

By combining the constants in equation (IV), there is obtained the following relationship for the cable force exerted on the guide pulley 42:

$$R_{Smax} = A - k_4 \cos \alpha \quad (V)$$

To achieve the several linear relationships illustrated in FIG. 4, it is necessary that the stress V in the helical compression spring 64 vary with α in the same manner as the force exerted by the cable 38 on the pulley 42:

$$V = A - k_4 \cos \alpha \quad (VI)$$

That the device shown in FIG. 2 can satisfy this condition will now be shown. The stress of the helical compression spring 64 varies according to the equation

$$V = V_{max} - k_5 h \cos \alpha \quad (VII)$$

wherein V_{max} is the highest stress reached when the boom 22 is in its position nearest a vertical position, k_5 is a proportionality factor derived from the spring constant, h is the spacing of the pivot axes at 24, 74, and α is the angle of inclination of the boom 22 relative to the horizontal. Equation (VII) is based on the assumption that the characteristic of the spring 64 is linear.

When the several constant factors are combined, equation (VII) may be written as:

$$V = B - k_6 \cos \alpha \quad (VIII)$$

when B is chosen equal to A in equation (VI) and k_6 is chosen to be equal to k_4 , the relationship of L_{max} to a becomes linear, as illustrated in FIG. 4.

FIG. 5 illustrates the percentage increase in load bearing capacity as a function of the angle of boom inclination when the conventional load limiting device is

replaced by that of the invention. FIG. 5 has been derived from the values of FIGS. 3 and 4 for effective boom lengths of 100 percent and 87.5 percent. It is evident that the maximum permissible load L_{max} is greatly increased for values of a which are intermediate the maximum and minimum.

FIG. 6 illustrates the variation in the maximum tensile stress in the boom 22 when the crane is equipped with the known load limiting device which is characterized by the curves of FIG. 3. The actual stresses are well below the permissible stress in the curve illustrating the condition of the boom of full length (100 percent), and the stresses are even lower in shorter booms, the permissible stress having a value of 2,400 kp/mm² in this instance.

FIG. 7 shows the maximum tensile stresses generated in booms of different lengths with the load limiting device of the invention whose characteristics are illustrated by FIG. 4. The actual stresses generated in the boom of 100 percent length when the crane is operated 20 at the full load tolerated by the limiting device differ from the design load over the entire range of boom inclination by not more than 5 percent so that the material of the boom is utilized to best advantage.

In the preceding discussion of numerical relationships, k_1 was considered to be absolutely constant, yet, many of the advantages of this invention are available when k_1 is at least substantially constant, but varies due to secondary factors, not considered above, to let the values of L_{max} differ by not more than 10 percent, and 25 preferably not more than 5 percent from the values of L_{max} defined by Equation (I) when k_1 is absolutely constant while a varies between a_{max} , the horizontal spacing of the lifting cable 38 and the pivot 34 when the boom is as close to a horizontal position as the 30 crane permits, and a_{min} , the horizontal spacing of the cable 38 and the pivot 24 when the boom is as close to a vertical position as is possible.

Similar considerations hold for the maximum tensile 40 stress in the boom 22. The material of construction of the boom (and of the column 18) is used to best advantage if the load carried by the cable 38 is limited in such a manner that the maximum tensile stress at permitted maximal loading of the cable is precisely constant and equal to the maximum design load. It would not be economical under most conditions to design a tower crane to such a precise performance, and the major advantages of this invention are available if the tensile stress in the boom differs by not more than plus/minus 10 percent, and preferably plus/minus 5 percent from a constant value while the spacing a varies between a_{min} and 45 a_{max} .

The load limiting device of the invention illustrated in FIG. 2 is, in effect, a mechanical comparator. The stress V in the spring 64 is generated in response to the angle of inclination α of the boom, or the spacing a between the pivot 24 and the depending cable 38, as projected into a horizontal plane. The cable 38 and the pulley 42 generate another force R_s in response to the magnitude of the load supported by the cable. The two forces V and R_s are both applied to the bracket 56 in such a manner as to oppose each other, and the bracket transmits the two forces, or their resultant force to the switch actuating abutment 60 which inactivates the winch 40 when the relationship of the forces V and R_s exceeds a predetermined value set, at least in part, by shifting the pivot axis of the bracket 56.

It will be appreciated that the mechanical comparator illustrated in FIG. 2 may be replaced by many analogous mechanical comparators or by their electrical and electronic equivalents.

It should be understood, therefore, that the foregoing disclosure relates only to a preferred embodiment of the invention, and that it is intended to cover all changes and modifications of the example of the invention herein chosen for the purpose of the disclosure 10 which do not constitute departures from the spirit and scope of the invention set forth in the appended claims.

What is claimed is:

1. A tower crane comprising:
  - a. a base structure;
  - b. an upright column upwardly extending from said base structure;
  - c. a pivot on said column near the upper end of the column;
  - d. an elongated boom having one longitudinal end portion secured to said column by said pivot for angular movement in a vertical plane;
  - e. adjusting means for varying the angular position of said boom in said plane;
  - f. a load lifting, elongated tension member depending from the other longitudinal end portion of said boom, whereby the spacing of said pivot and of said member projected into a horizontal plane, varies in response to the variation of said angular position between a minimum value and a maximum value;
  - g. winch means for longitudinally raising and lowering said tension member and a load attached thereto; and
  - h. load limiting means for inactivating said winch means when a load attached to said tension member exceeds a predetermined value,
1. said load limiting means including means for varying said predetermined value as a function of said projected spacing during said variation of the angular position of said boom to satisfy the equation

$$L_{max} = L_{0max} - k_1 a$$

wherein L_{max} is predetermined value of said attached load,

a is said projected spacing,

L_{0max} is the value of L_{max} when $a = a_{min}$,

a_{min} being minimum value of said projected spacing, and

k_1 is a proportionality factor and substantially constant.

2. A tower crane as set forth in claim 1, wherein the values of L_{max} differ by not more than 10 percent from the values of L_{max} defined by said equation when k_1 is constant while a varies between a_{max} and a_{min} , a_{max} being said maximum value.

3. A tower crane as set forth in claim 1, wherein the values of L_{max} differ by not more than 5 percent from the values of L_{max} defined by said equation when k_1 is constant while a varies between a_{max} and a_{min} , a_{max} being said maximum value.

4. A tower crane as set forth in claim 1, wherein the maximum tensile stress in said boom differs by not more than plus/minus 10 percent from a constant value while said a varies between a_{min} and a_{max} , a_{max} being said maximum value.

5. A tower crane as set forth in claim 1, wherein the maximum tensile stress in said boom differs by not

more than plus/minus 5 percent from a constant value while said a varies between a_{min} and a_{max} , a_{max} being said maximum value.

6. A tower crane as set forth in claim 1, wherein said load limiting means include means responsive to said spacing a for generating a first force, means responsive to said attached load for generating a second force, and comparator means for generating an inactivating signal when the relationship of said forces exceeds a predetermined value, said winch means responding to said signal.

7. A tower crane as set forth in claim 6, wherein said comparator means include a switch and a movably mounted switch actuating member, a pulley member

mounted on said switch actuating member, said load lifting member being trained over said pulley member, said pulley member and said tension member constituting elements of said means for generating said second force, and means transmitting said first force to said switch actuating member to resist said second force.

5 8. A tower crane as set forth in claim 7, wherein said means for generating a first force include a spring, first motion transmitting means interposed between said boom and said spring, and second motion transmitting means interposed between said switch actuating member and said spring.
